(57) **CLAIM**

The ornamental design for a vehicle exhaust tip having a sealed front section and a lower exhaust port, as shown and described.

DESCRIPTION

FIG. 1 is a perspective view of a vehicle exhaust tip having a sealed front section and a lower exhaust port showing my new design. The vehicle tail pipe is shown in broken lines for illustrative purposes only and forms no part of the claimed invention,

FIG. 2 is a right side elevational view thereof, the left side being a mirror image; thereof;

FIG. 3 is a top plan view thereof;

FIG. 4 is a bottom plan view thereof; and,

FIG. 5 is a front elevational view thereof.
